UNITED STATES PATENT OFFICE

2,524,307

STEAM GENERATOR

John Isom Cantrell, Mobile, Ala.

Application January 4, 1949, Serial No. 69,223

1 Claim. (Cl. 219—38)

1

The present invention relates to improvements in steam generators and has for an object to provide an electrically heated steam generator in which a high thermal efficiency is secured by an exceedingly simple construction.

Another object of the invention is to so mount the electric heating unit that it may be readily attached and removed from the water space of the boiler.

With the foregoing and other objects in view, the invention will be more fully described herein-after and more particularly pointed out in the appended claim.

In the drawings, in which like parts are denoted by the same reference characters throughout the several views,

Figure 1 is a side elevational view of an improved steam generator or boiler constructed in accordance with the present invention with parts broken away and parts shown in section;

Figure 2 is an end elevational view of the same;

Figure 3 is a sectional view, taken on a greatly magnified scale, of one of the two electrical terminals employed for suspending the resistance coil across the steam generator and to receive the external circuit connections; and

Figure 4 is a side elevational view taken on the same scale and showing the plug portion of such terminal and its connections.

Referring more particularly to the drawings, 12 designates a resistance coil which is stretched across the lower portion of the water space of the steam generator 17 which may be in the form of a cylindrical boiler.

The external electric circuit is indicated at 13 and 13A and connects the resistance coil 12 with any outside source of electric current whereby the coil 12 becomes energized. The external circuit may be under the control of a manual switch if desired.

The terminals carrying the resistance coil 12 in the cylindrical boiler or steam generator 17 are specially constructed. The terminals 14 and 15 are substantially identical, and one such terminal 14 is shown in Figures 3 and 4 to comprise a casing block 56 welded or otherwise secured to the end head of the steam generator 17 and having an internal bore 57 and a reduced externally threaded projecting neck 58 to which is threaded a cap 59 to enable the same to be removed. The cap is formed with a central opening 60.

The cap holds in place the head 61 of a brass plug 29 having a central opening for receiving therethrough the mica or other non-conducting sleeve 30. Such sleeve is pierced centrally to receive a center wire or rod 31 having the terminal eyes 62 and 63 to receive the external circuit wire 13 and the inner end of the resistance coil 12 respectively. The center rod or wire 31 is composed of copper or other conducting material.

In operation, the passage of electric current

through the resistance coil 12 causes the coil to become heated in a well-known manner and to consequently heat the body of water surrounding the same to eventually convert such water into steam which rises to the steam space of the generator 17 and passes therefrom through the pipe 18 and into the steam dome or valve chest of a steam engine.

By unscrewing the caps 59 at both ends the entire resistance wire 12 and its plugs may be withdrawn through the opening 57 at one end of the boiler. For the purpose of unscrewing the cap 59, it will be understood that the opening 60 is wider than the eye 62.

In this way the resistance wire may be introduced and removed in a very simple operation.

While I have disclosed herein the best form of the invention known to me at the present time, I desire it to be understood that I reserve the right to make changes and modifications in the herein described embodiment of the invention provided such changes fall within the scope of the following claim.

What I claim is :

A steam generator comprising a boiler having opposed end walls and a water space, said end walls having aligned openings, an electric resistance heating coil stretched across the lower portion of the water space within the boiler and being of a diameter less than the diameter of the end wall openings to permit passing of the coil through such openings, casing blocks secured to the outside faces of said end walls and having internal through bores of substantially the same diameter as the openings and registering with such openings, said blocks having threaded necks in their outer portions, plugs slidable into and out of said bores and having heads wider than the bores for encountering the outer ends of the necks to prevent the plugs being drawn through the bores into the boiler by the weight and tension of the resistance coil, non-conducting sleeves fitted through said plugs, conductor rods fitted through said sleeves and having internal connections for electrical connection to said resistance coil and for the mechanical support of the coil in its stretched condition across the water space and also having external connections for including in an external electric circuit, and threaded caps removably mounted to said threaded necks and having outer end discs engaging said heads to hold the heads against the necks, said discs having openings wider than said connections.

JOHN ISOM CANTRELL.
